UNITED STATES PATENT OFFICE.

DAVID F. HAYNES, OF BALTIMORE, MARYLAND.

DESIGN FOR A EWER OR JUG.

SPECIFICATION forming part of Design No. 21,307, dated January 19, 1892.

Application filed December 26, 1891. Serial No. 416,244. Term of patent 3½ years.

To all whom it may concern:

Be it known that I, DAVID F. HAYNES, a citizen of the United States, residing at Baltimore, Maryland, have invented and produced a new and original Design for a Ewer or Jug, of which the following is a specification, reference being had to the accompanying drawings, forming a part hereof.

Referring to the said drawings, Figure 1 is an exterior side elevation of the ewer, and Fig. 2 a top view of the same.

I describe the ewer or jug as follows: Its base A is circular. The body B is a frustum of a spheroid, terminating at the upper end in an inverted frustum of a cone. At the junction of the spheroidal and frusto-conical portions of the body is a hollow-faced band a. The lip b is decorated with a foliated design, and the two side faces of the body have beads

c, with a general outline effected by bringing together four segments of circles. Within the beaded spaces are four flowers apparently on a single stem with leaves. The remaining surface of the body is covered with representations of daisies of different sizes, which, like the flowers, are in relief. The handle C has a foliated decoration and is attached at its upper end to the frusto-conical portion of the body and at its lower end to the spheroidal part.

I claim as my invention—

The design for a ewer or jug, as herein shown and described.

DAVID F. HAYNES.
